(57) **CLAIM**

The ornamental design for a bottle, as shown and described.

DESCRIPTION

FIG. 1 is a top, front, and right side perspective view of a bottle depicting the new design;

FIG. 2 is a front elevational view thereof;

FIG. 3 is a right side elevational view thereof;

FIG. 4 is a top plan view thereof; and,

FIG. 5 is a bottom plan view thereof.

The dash lines shown in the drawings are for illustrative purposes only and form no part of the claimed design.

The dash-dot-dash lines immediately adjacent to the shaded areas in the drawings represent unclaimed boundaries of the claimed design. The remaining dotted lines in the drawings are for illustrative purposes only and form no part of the claimed design.

1 Claim, 4 Drawing Sheets*Fig. 1*
